UNITED STATES PATENT OFFICE.

ASHER LAMBERT, OF NEWARK, NEW JERSEY.

HOISTING AND CONVEYING APPARATUS.

978,312.

Specification of Letters Patent. Patented Dec. 13, 1910.

Original application filed May 3, 1906, Serial No. 314,929; Divided and this application filed February 10, 1909. Serial No. 477,157.

To all whom it may concern:

Be it known that I, ASHER LAMBERT, a citizen of the United States, and a resident of Newark, in the county of Essex and State of New Jersey, have made certain new and useful Improvements in Hoisting and Conveying Apparatus, of which the following is a full, clear, and exact description.

This invention relates to automatic apparatus employing buckets for excavating, filling, hoisting, removing, and discharging earth, coal or other materials, and in the method of operating such buckets.

The object of the invention is to obviate the evil effect of heat generated by friction in lowering the bucket and to provide a separate independent detached means but operating in connection with the hoisting engine so that said means may be replaced or shifted about as occasion may require.

The improvement in the method of operating the bucket consists in employing two ropes which are fixed to the bucket, one being a closing and hoisting rope, the other an opening and lowering rope. The hoisting rope is connected with one drum of a hoisting engine, the lowering rope is connected to a separate independent means which is detached from the engine. The bucket is then hoisted by one rope, its support shifted to the second rope, the load discharged and the bucket lowered while supported by said second rope.

The accompanying drawings illustrate the invention.

Figure 1 is a side elevation of the bucket, hoisting engine, a derrick, and the independent means for lowering the bucket. Fig. 2 is a top plan view. Fig. 3 is a perspective view of the separate detached independent means for gradually lowering the bucket.

In Fig. 1, there is a hoisting engine *h* having rotating drums *d*, *e*, and *f*. The derrick has a vertical mast *10*, a swinging boom *11*, a turn table therefor *12*, and a stiff leg or brace *13*. The bucket *b* is shown of the clam shell pattern. The rope *r* passes around the pulley *p*; when supported by the rope *r* the bucket is automatically closed. The rope *m* is the lowering rope and is connected to the joint or hinge *j* of the bucket *b*; when supported upon the rope *m* the bucket automatically opens and discharges its load. The rope *r* passes over the pulley *t*

and is operated by one of the drums either *d* or *e*. The rope *n* is operated by one of the drums *d* or *e* and is reeved through the pulleys *15*, *16* and *17*, its outer end being fixed at the point *18*; this rope when operated raises and lowers the boom *11*. The rope *o* passes around the winches *f*, *f*; the function of the rope *o* and winches *f* is to turn the bull wheel or turn table *12*. There are a series of framing or foundation timbers *i* laid in position and secured together to support the derrick, and there is a frame *k* upon which the hoisting engine is fixed. There are controlling devices *20* and *21* by which the drums of the engine are thrown into gear and started and checked in their movement in a well known manner.

A means for operating the lowering and opening rope *m* is shown in Fig. 3; this consists of a pulley *30* on a shaft *31* in suitable bearings carried by the brackets *32*. There are a pair of these brackets and they are located upon an independent foundation *33*. There is a brake wheel *34*, a strap friction brake *35* with wooden contact blocks *80* or shoes *36* and a controlling lever *37* designed to be operated by the foot. This device may be located on the frame *k* of the engine as shown in Fig. 1 or may be separately supported in a detached position as shown in the plan view, Fig. 2. It is composed of comparatively light material so as to be easily portable and it may be easily substituted by a duplicate device if it becomes heated or injured. The opening and lowering rope *m* passes over the pulleys *s*, *q* and *w* to the pulley *30*, thence over the pulley *40* supported from the stiff leg *13* and is fixed to a point *41* on the stiff leg *13*. On the rope *m* between the points *40* and *41* there is a weight *x* having a pulley *42*. This pulley takes up the slack in the rope *m* as the hoisting rope *r* raises the bucket *b*.

The operation is as follows: The bucket *b* is in contact with the earth or broken stone to be removed. The engine is started to hoist on the rope *r*, the pulley *p* is thus turned and the bucket is closed to grab the earth and is hoisted to the desired height. The boom *11* is turned and hoisted to bring the bucket *b* over the desired discharge point; the weight *x* takes up the slack in the rope *m*, it is now desired to discharge the bucket, the friction brake *37* is operated by the foot, the rope *m* is held, the hoisting

rope r is slackened, the weight of the bucket is thrown onto the rope m , the bucket b automatically opens and discharges and while the bucket b is supported by and from the 5 rope m , the friction brake 37 is so manipulated as to allow the bucket to gradually descend. In this manner the heat and friction due to applying the brake to the hoisting drum is avoided. By the use of the 10 means described and the method of operation described the hoisting and lowering may be continued rapidly and indefinitely without heating the operating parts of the hoisting drum and without generating sufficient accumulated heat in the means for 15 lowering the bucket to cause trouble or inconvenience.

By the use of the means described a two drum engine which is commonly carried in 20 stock and is available at short notice may be made to perform the duties of a three drum engine.

What I claim and desire to secure by Letters Patent is:

25 1. The combination of a self opening bucket, a hoisting rope, a controlling rope,

means for hauling on one of said ropes to raise the bucket, means for shifting the weight of the bucket from one rope to the other and a separate, independent means for 30 lowering said bucket while supported upon said second rope.

2. The combination of a self opening bucket, a hoisting rope, a controlling rope, means for hauling on one of said ropes to 35 raise the bucket, means for shifting the weight of the bucket from one rope to the other and a separate independent means for gradually lowering said bucket while supported upon said second rope. 40

3. The combination of a self opening bucket, a hoisting rope, a controlling rope, means for hauling on one of said ropes to raise the bucket, means for shifting the weight of the bucket from one rope to the 45 other and a separate detached means for gradually lowering said bucket while supported upon said second rope.

ASHER LAMBERT.
